US0D1023916S

(12) **United States Design Patent** (10) Patent No.: **US D1,023,916 S**
(45) Date of Patent: ** Apr. 23, 2024

(54) **WIRELESS CHARGER**

(71) Applicant: **Shenzhen AI Infinite Electronics Co., Ltd.**, Shenzhen (CN)

(72) Inventors: **Lifeng Luo**, Shaoyang (CN); **Xiping Zhao**, Shenzhen (CN)

(73) Assignee: **Shenzhen AI Infinite Electronics Co., Ltd.**, Shenzhen (CN)

(**) Term: **15 Years**

(21) Appl. No.: **29/850,522**

(22) Filed: **Aug. 22, 2022**

(30) **Foreign Application Priority Data**

May 11, 2022 (CN) 202230276532.3

(51) LOC (14) Cl. **13-02**

(52) U.S. Cl.

USPC **D13/107**

(58) **Field of Classification Search**

USPC D13/103, 107, 108, 118, 119, 183;
D14/224, 240, 251, 253, 432, 433, 434,
D14/447, 457; D10/2

See application file for complete search history.

(57) **CLAIM**

The ornamental design for a wireless charger, as shown and described.

DESCRIPTION

FIG. 1 is a front perspective view of a wireless charger, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 a top view thereof; and,

FIG. 8 is a bottom view thereof.

1 Claim, 8 Drawing Sheets
